CAM CONTROLLED CONTOUR POLISHING

Forrest R. Whitcomb, Worcester, Mass.

Application October 19, 1949, Serial No. 122,203

8 Claims. (Cl. 51—84)

1

This invention relates to new and improved machines for contour abrading, polishing, and buffing, the polishing wheels being moved relative to the work under control of a cam, which cam may be generated from the work piece upon the same machine if desired.

The principal object of the invention resides in the device as above described and including a pair of polishing or abrading wheels which are moved in and out to and from each other according to a cam, at opposite sides of a work piece, and comprising means for making them completely uniform with respect to each other as to movement and pressures, there being a roll at each side of the work piece so as to operate on both sides thereof simultaneously.

Another object of the invention resides in the provision of a floating cylinder which is secured to a lever on which is rotatably mounted a polishing wheel, said cylinder being provided with a piston rod which is secured to another lever carrying another polishing wheel and adapted to operate on the opposite side of the work piece; in combination with a balanced valve for controlling the relative motion of the piston rod relative to the valve housing, said valve being controlled and operated through a linkage system from the cam whereby the two working rolls are moved toward and away from each other uniformly and in unison depending upon the contour of the cam.

Another object of the invention resides in a machine as above stated where a work piece may be passed between the rolls and upon locking of the control linkage to the valve housing, causes the cam follower to be moved, so as to outline the cam which may then be cut according to the outline.

Other objects and advantages of the invention will appear hereinafter.

Reference is to be had to the accompanying drawing in which

Fig. 1 is a view in end elevation of a machine according to the present invention, parts being in section;

Fig. 2 is an enlarged vertical section through the cylinders and valves; and

Fig. 3 is a top plan view of the cylinder housing.

Reference is herein made to my co-pending application, Serial No. 92,240 filed May 9, 1949, wherein some of the parts are the same as in this case, the machine illustrated in said application being the same as the one herein, this present invention illustrating an attachment therefor.

2

For example, the vertically reciprocating head 10, piston rod 12, piston 14, and main cylinder 16 are all just as in the previously filed application and the same is true of the work W which, however, in the present case is shown as having irregular outlines.

Also, the reference numeral 18 herein indicates the four-way valve 92 of the previous case and the reversing valve 20 is the same as that shown at 34, and it is to be understood that the entire hydraulic system is the same so that it need not be disclosed, except as appears in Fig. 1 herein.

However, it is to be understood that with the valve 20 in one position, an impulse is impressed in a line 22; whereas if the valve is in the other position, the impulse is impressed in line 24, but each of these lines is controlled by its own hand valve 26 and 28 for reasons which will appear hereinafter.

The reference numeral 30 indicates the base or end plate for the entire machine and on it are mounted a pair of pins 32 pivotally mounting interengaged sector gears 34 arranged as bell cranks with levers 36 and 38. The upper ends of the levers 36 and 38 terminate in bearings which rotatably mount the polishing or abrading rolls 40 which besides rotating, have a substantially rectilinear motion as indicated by the horizontal arrows, the vertical arrows indicating the direction of reciprocation of the work piece between the rolls 40.

It will be well understood that if the work piece W is irregular or tapers in outline, it is desirable to move the polishing rolls in conformance therewith so as to apply equal abrading pressures on the work piece throughout the entire surface thereof.

There is provided a cylinder 42 which is connected at 44 to lever 36 intermediate the ends of the latter, and a piston rod 46 having a piston 48 in the cylinder extends outwardly therefrom and is pivoted at 50 intermediate the ends of lever 38, this cylinder being otherwise unsupported and floating.

It will be clear that pressure at the right hand side of piston 48 will cause the rolls to separate and pressure at the left hand side thereof will cause the rolls to come together with equal pressure or force.

The pressures in cylinder 42 are provided by means of a line 52 entering a valve housing 54 and passing through a hollow valve element 56 to the opposite side thereof so that the valve element 56 is completely balanced by having equal pressures at either side.

A port 58 leads through a passage 60 to a port 62 at the right hand end of cylinder 42; and a similar port 64 leads through a passage 66 to the left hand end of cylinder 42 at 68. Thus with the parts as shown in Fig. 2, there is no pressure exerted at either side of the piston, but a slight movement to the right of valve element 56 applies pressure to the right hand side of the piston; and a slight movement of valve element 56 to the left will apply pressure to the left hand side of the piston 48. The valve element 56 is controlled by means of a rod 70 rectilinearly movable by means of a lever 72 pivoted at 74, lever 72 having a connecting link 76 pivoted to a cam follower lever 78 provided with a follower 80 pressed 15 against the cam 82 by means of a spring 84. The cam 82 may be connected to the head 10 and moves therewith.

Thus, as the cam 82 moves down, the follower 20 80 causes lever 78 to oscillate, in turn oscillating lever 72 and moving link 76 to actuate valve member 56 as above stated, the gear segments 34 maintaining the relative positions of the levers 36 and 38.

It is desirable especially with tapered or irregular work pieces, that upon reaching the end of the stroke, the pressure on the rolls 40 be increased to achieve a rapid reversal. It is usually preferable to run the rolls apart at the ends of the stroke to avoid rounding off the corners, but this slows up the operation of the machine hence the desirability to bring the rolls back quickly for the next stroke.

To accomplish this purpose there is provided a hydraulic cylinder 88 having a piston rod 90 35 spring pressed downwardly by a spring 92 to tend to draw a bell crank 94 in a clockwise direction, one arm of the bell crank being pivotally connected at 96 to the bottom end of lever 78. An impulse received through line 98 causes the piston 40 90 to rise to a degree limited by a set screw 100 and thus pivot the lever 78 in a direction which will cause the link 76 and lever 72 to actuate valve 56 to tend to bring the rolls 40 toward each other. This entire hydraulic device is mounted 45 on a plate 102 which may be adjusted by means of a screw and a nut arrangement 104 on the base 30.

It will be seen that the hydraulic impulse in line 98 will be achieved at the end of each stroke 50 due to the reversal and four-way valves, and these impulses will be received in lines 22 and 24 which can be closed by valves 26 and 28 in cases where the compensation is desired only at the top of the bottom stroke. Further, any wear in the 55 linkage can be taken up by adjusting parts 100 and 102.

A screw 106 is provided to fix rod 70 to the housing 54, whereupon the action of the device will be the reverse of that stated above. That 60 is, as the head 10 descends, the rolls 40 are moved to and from each other and this causes the link 76 to move the lever 78 to describe an outline by roller 86, which outline may be cut out, forming the cam.

Having thus described my invention and the advantages thereof, I do not wish to be limited to the details herein disclosed otherwise than as set forth in the claims, but what I claim is:

1. Apparatus of the class described comprising a pair of movable supports, an abrading roll on each support, floating hydraulic cylinder and piston means respectively connected to the supports to move the latter toward and away from each other, a valve controlling the cylinder and

5 piston to determine the spacing of the supports, a moving cam, and a cam follower therefor connected to the valve to control the latter and thereby cause the supports and abrading rolls to move toward and away from each other according to the cam contour.

2. Apparatus of the class described comprising a pair of movable supports, an abrading roll on each support, floating hydraulic cylinder and 10 piston means respectively connected to the supports to move the latter toward and away from each other, a valve controlling the cylinder and piston to determine the spacing of the supports, a moving cam, a cam follower therefor connected to the valve, to control the latter and thereby cause the supports and abrading rolls to move toward and away from each other according to the cam contour, and gearing interconnecting the supports for uniform simultaneous movement.

3. Apparatus of the class described comprising a pair of movable supports, an abrading and polishing roll on each support, a hydraulic cylinder connected to one support, a piston and rod for the cylinder connected to the other support, means effective to apply pressure to either side of the piston selectively according to a cam to separate the supports or to draw the same toward each other, a cam for said means, a cam follower movable by the cam to control the said means, and means to move the cam through a cycle.

4. Apparatus of the class described comprising a pair of movable supports, an abrading and polishing roll on each support, a hydraulic cylinder connected to one support, a piston and rod for the cylinder connected to the other support, means effective to apply pressure to either side of the piston selectively according to a cam to separate the supports or to draw the same toward each other, a cam for said means, a cam follower movable by the cam to control the said means, and means to move the cam through the cycle, said cylinder and piston being otherwise unsupported, and means effective to cause the supports to move in unison.

5. Apparatus of the class described comprising a pair of movable supports, an abrading roll on each support, a hydraulic cylinder and piston means to move the supports toward and away from each other, a valve controlling the cylinder and piston, a cam, a cam follower connected to the valve to actuate the latter by movement of the cam follower, work reciprocating means, said cam follower being connected to the work reciprocating means for movement thereby.

6. Apparatus of the class described comprising a reciprocating head, means to secure work pieces thereto, a cam on the head for reciprocation thereby, a movable cam follower, a valve movable according to the cam follower, a cylinder, piston, and piston rod controlled by the valve, a lever pivoted to the cylinder, another lever pivoted to the piston rod, a working roll on each lever, and gearing connecting the levers for uniform swing thereof, the work pieces being located to be reciprocated between the rolls.

7. Apparatus of the class described comprising a reciprocating head, means to secure work pieces thereto, a cam on the head for reciprocation thereby, a movable cam follower, a valve movable according to the cam follower, a cylinder, piston, and piston rod controlled by the valve, a lever pivoted to the cylinder, another lever pivoted to the piston rod, a working roll on each lever, and gearing connecting the levers

for uniform swing thereof, the work pieces being located to be reciprocated between the rolls, a link connecting the cam follower and valve, and means to fix the link to the valve to cause in-operation of the valve, whereby the work piece will cause movement of the cylinder and cam follower to outline the cam.

8. Apparatus of the class described comprising a pair of movable supports, an abrading roll on each support, hydraulic cylinder and piston means to move the supports toward and away from each other, a valve controlling the cylinder and piston, a cam, and a cam follower connected to the valve, another cylinder, a piston and rod therefor, the latter being connected to the cam follower to move the latter in addition to the cam originated movement, whenever the second named cylinder is energized, a third cylinder to

reciprocate the cam, a reversing mechanism therefor, and means selectively operable by the reversing mechanism to energize the second named cylinder at the ends of the stroke of the third cylinder.
